UNITED STATES PATENT OFFICE

133,635

DESIGN FOR AN AIRPLANE

Robert W. Huzzard, York, Pa., assignor of two-thirds to George H. Whiteley, III, York, Pa.

Application August 7, 1941, Serial No. 102,719

Term of patent 14 years

To all whom it may concern:

Be it known that I, Robert W. Huzzard, a citizen of the United States, and a resident of York, in the county of York and Commonwealth of Pennsylvania, have invented a new, original, and ornamental Design for an Airplane, of which the following is a specification, reference being had to the accompanying drawings, forming a part thereof.

Figure 1 is a top perspective view of an airplane embodying my new design with the wheels shown in landing position,

Figure 2 is a front elevational view of the airplane showing the wheels in landing position,

Figure 3 is a top perspective view of the airplane showing the wheels retracted, and

Figure 4 is a bottom perspective view of the airplane showing the wheels retracted.

I claim:

The ornamental design for an airplane, as shown.

ROBERT W. HUZZARD.
